(57) **CLAIM**

The ornamental design for an electrical connector protective cover, as shown and described.

DESCRIPTION

FIG. 1 is a front elevation view of an electrical connector protective cover showing our new design;

FIG. 2 is a back elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top perspective view thereof; and,

FIG. 8 is another perspective view thereof, in use condition.

The dash-dot-dot broken line portion of the figure drawings is included to show unclaimed subject matter only and forms no part of the claimed design.
